[57] ABSTRACT

The invention consists of a railway wagon body made of metal which has curved sides suspended from longitudinal stringers to eliminate side stiffeners and heavy floor plates to effect a saving in manufacturing cost and in tare weight to increase the pay load. The body is supported on curved bolsters adjacent each end and is internally strengthened by means of bulkheads.

RAILWAY WAGON

This invention relates to an improved railway wagon and more particularly to a goods wagon suitable for transporting such goods as iron ore, bauxite, coal, cement and other bulk materials.

In recent years, considerable attention has been paid to the design of transport vehicles with a view to reducing the tare weight while maintaining adequate strength so that the pay load can be increased without adding to the weight to be moved by the prime mover. Any economies achieved in vehicle weight enable additional loads to be carried without additional transport costs. One effective means of reducing vehicle weight is to use light metals such as aluminium alloys wherever possible in place of the steel previously used but, in general, the design of wagons using aluminium alloys has merely followed the design of steel wagons without any real attempt being made to redesign so that maximum weight savings can be achieved.

It is an object of this invention to provide a railway wagon of reduced weight compared with wagons previously manufactured.

A subsidiary object of the invention is to provide a rotary type dump wagon (i.e., a wagon which may be placed in a roll-over mechanism for unloading) having the above advantage.

The wagon of the invention can be constructed primarily from aluminium alloys to achieve maximum weight saving, but it will be realised that the design is also applicable to steel construction and particularly to wagons constructed from high tensile steel.

According to the invention there is provided a railway wagon body comprising a longitudinal centre sill, a bolster of curved cradle formation supported from said sill at or adjacent each of its ends, a skin or shell having its lower area of curved configuration to match the curve of said bolsters, a plurality of spaced bulkheads welded transversely of and within said skin or shell, the external configuration of each bulkhead being substantially identical with the required cross-sectional internal shape of the shell, each bulkhead extending upwardly substantially to the upper extremity of the shell at least adjacent each side of the shell, and a longitudinal stringer on each side of said wagon supported from said bulkheads, the upper sections of said shell being curved inwardly and connected to said stringers.

In order that the invention may be more readily understood, it will now be described by way of example with reference to a particular embodiment, illustrated in the accompanying drawings, wherein:

FIG. 1 is a plan view of a wagon according to the invention.

FIG. 2 is a side elevational view of the wagon partly in cross-section.

FIG. 3 is a cross-sectional view on line 3-3 of FIG. 2.

FIG. 4 is a cross-sectional view on line 4-4 of FIG. 2.

The wagon of this embodiment has a centre sill 10 which is preferably a box section made up from a pair of spaced, extruded aluminium sections in the form of channels 12 arranged with their webs 14 in an vertical plane. The lower flanges of the channels are connected by welding to a plate 16 and the upper flanges may be similarly connected.

Alternatively the upper edges of the channels 12 may be provided with integrally-extruded additional flanges 18 as illustrated in FIG. 4, extending in the opposite direction to the standard channel flanges and providing steps 20 on the upper surfaces of the channels for a purpose which will hereinafter appear. The free edges of channels 18 are placed in abutting relationship and welded together.

Adjacent each end of the sill 10 a bolster 22 of curved cradle configuration is welded to the sill. Each bolster is of box section, having upper and lower flanges 24, 26 with a pair of spaced connecting webs 28. If so desired, the lower plates 16 of the sill section 10 may be located only adjacent the bolsters 22 and appropriate bridging connections 32 may be welded to the lower parts of the channel sections at spaced locations in the length of the sill.

The body shell 34 is supported on the bolsters 22 and has a curved configuration substantially throughout. In cross-section, proceeding from the centre line of the wagon, the shell has a substantially flat base where it sits on the sill 10 and for a short distance beyond the sill. The shell then follows a relatively small radius through an angle of approximately 90° to the point of greatest width. The upper section of the shell curves inwardly at a greater radius.

The sides of the shell are connected at their upper edges to longitudinal stringers 36, and the overall curve selected for the shell is such that, assuming the wagon to be fully loaded and the shell to be substantially supported from said stringers, the stress in the shell approaches pure tension with little if any bending stress. This enables the thickness of the skin to be reduced to the minimum subject to practical considerations such as the wear and tear and knocks which railway wagons receive in use.

The ends 38 of the shell may be of curved configuration as seen in plan view, but are preferably straight and slope inwardly from their upper edges towards their lower edges as illustrated in the drawings.

The shape of the shell is set and maintained by means of internal bulkheads 40. Each bulkhead in the present case is substantially in the shape of a horseshoe having a relatively heavy spreader section in the lower area of the shell and tapering upwardly at each side of the shell to the upper edges of the latter to act as supports for stringers 36. The outer surface of each bulkhead 40 is shaped to conform to the required internal shape of the shell.

Each bulkhead is of box section consisting of a pair of spaced plates 42 upstanding from the internal surface of the shell and with a cover plate 44 welded to the free edges of plates 42. In the lower section of the shell cover plate 44 is arranged substantially parallel to the inner surface of the shell but approaches more closely to the shell in its upper area where plates 42 are tapered. The box section is closed on each side of the shell by a narrow longitudinal plate 46.

The shell extends substantially the full length of the sill as seen in FIG. 2 and the end walls 38 of the body are welded inside the ends of the shell as also shown in FIG. 2 and are strengthened by horizontal stiffeners 58 of I-section welded horizontally across their end surfaces. The stiffeners are also welded to the internal surface of the shell. A pair of transverse stringers 62 are welded to the ends of longitudinal stringers 36 and to the upper edges of the ends 38 of the shell. Preferably

the longitudinal stringers are provided with grooves 64 as illustrated in FIG. 3 adapted to receive the upper edges of the shell. The shell is made in two halves, each of which has its upper edge engaged with one of the longitudinal stringers and its lower edge abutted against one of the shoulders 20 of sill 10.

Provision must be made to enable the wagon to be tipped by the unloading mechanism without damage to the body shell. The tipping mechanism usually includes a pair of vertically spaced horizontal beams arranged at each side of the track and adapted to be moved horizontally to engage the sides of the wagon preparatory to the tipping action. To resist the force applied by these beams, suitable arrangements are made in the area of each of the bulkheads. Preferably there are three such bulkheads, one in alignment with each of the two bolsters adjacent each end of the wagon, and the third located approximately at the centre of the length of the wagon.

For engagement by the upper beam a number of longitudinal plates 70 are attached to the outer surface of the shell at the position at which the shell is approximately vertical, i.e., at the point of maximum outward projection of the shell. Plates 70 are preferably made of manganese steel for durability. In this case they are attached to the surface of the shell by means of bolts. In cases where plates 70 are made from an aluminium alloy they may be welded to the shell.

For engagement by the lower beam there is provided, adjacent each end of the shell, a pad 72 bolted or welded to each end of each bolster. In addition there is provided adjacent the centre bulkhead a bracket 74 which is welded to the outer surface of the shell and which is provided with a pad 76.

It will be clear to those skilled in the art that the wagon described hereinabove makes very efficient use of the construction materials used and enables the weight of a wagon for a given volumetric capacity to be considerably reduced. It follows that, by use of the wagon of the invention, the pay load to be drawn by a

given locomotive is substantially increased.

I claim:

1. A railway wagon body comprising a longitudinal centre sill, a bolster of curved cradle formation supported from said sill at or adjacent each of its ends, a skin or shell having its lower area of curved configuration to match the curve of said bolsters, a plurality of spaced bulkheads welded transversely of and within said skin or shell, the external configuration of each bulkhead being substantially identical with the required cross-sectional internal shape of the shell, each bulkhead extending upwardly substantially to the upper extremity of the shell at least adjacent each side of the shell, and a longitudinal stringer on each side of said wagon supported from said bulkheads, the upper sections of said shell being curved inwardly and connected to said stringers.

2. A railway wagon body as claimed in claim 1 including three of said bulkheads, one substantially in alignment with each of said bolsters and the third located substantially mid-way between said bolsters.

3. A railway wagon body as claimed in claim 1 wherein the external configuration of each of said bulkheads comprises a substantially flat base connected with a curved section of relatively small radius through an angle of approximately 90°, and an upper section curving inwardly about a relatively large radius.

4. A railway wagon as claimed in claim 3 including a plurality of plates each attached by welding to the outer surface of said shell along its line of greatest outward projection and in alignment with each side of each of said bulkheads for engagement by an upper beam of a tipping mechanism and a plurality of plates attached to the outer extremities of said bolsters and to brackets arranged between said bolsters for engagement by a lower beam of said tipping mechanism.

5. A railway wagon body as claimed in claim 1 having end walls which slope downwardly and inwardly and are welded within said shell.
